FIG. 4.

INVENTOR:

Jennie M. Nelson
BY David E. Carlsen
ATTORNEY.

UNITED STATES PATENT OFFICE.

JENNIE M. NELSON, OF ST. PAUL, MINNESOTA.

HAT BANDEAU.

Application filed May 27, 1925. Serial No. 33,143.

My invention relates to a bandeau for hats and the object is to provide a simple, efficient and inexpensive device particularly adaptable for ladies' or children's hats. A further object is to eliminate the use of pads or fillers of various kinds and thereby increase the comfort of the wearer of the hat.

In the accompanying drawing:

Fig. 1 is a transverse vertical sectional elevation of the front half of a hat and my bandeau secured in position.

Fig. 2 is a longitudinal sectional elevation of a hat with my bandeau, in actual use on the head of a person.

Fig. 3 is a rear elevation of one of my bandeaus and Fig. 4 is a sectional view on the line 4—4 in Fig. 3.

Referring to the drawing by reference letters A represents any type of hat in which it is desired to place a bandeau. The latter comprises an elongated preferably quadrangular section of light but stiff fabric B such as crinoline in one or more layers. The top, ends and bottom edges of the cloth B are protected and reinforced by suitable braid or edging material C, D and E respectively, said edging being suitably stitched to the cloth.

The cloth or web B after first being cut to the desired size is then rolled or otherwise treated to give it an arcuate form. The lower edge E is preferably longer than the upper edge C and during the rolling of the web its lower part including edging

E is stretched outwardly said edging E being subsequently sewed to the hat. Thus the lower part of the cloth will be permanently flared outwardly to the edging E which is of a larger curvature than the upper edging C. When the edging E is 35 stitched as at F (Figs. 1 and 2) to the inner and lower surface of the crown of a hat, the upper edge C being of smaller curvature the main area of the web B will be 40 spaced inwardly from the hat crown, said 45 web gradually flaring out to the edging E.

In Fig. 2 a hat with my improved bandeau is shown on a head G, the bandeau clearly shown in cross section and bearing against the head. The air space between the hat 50 and the head provides coolness and comfort to the wearer and where the bandeau contacts with the hair the yielding hat retaining action of the bandeau does not press the hair sufficiently to create discomfort or disarrange the hair in any manner when the hat is removed.

What I claim is:

A hat bandeau comprising a substantially 60 quadrangular shaped section of netting material having a head contacting surface which is convex between its upper and lower edges and concave between its opposite side edges, and in which the upper portion is 65 spaced from the hat when the lower edge portion is attached to the hat.

In testimony whereof I affix my signature.

JENNIE M. NELSON.
